MACHINE FOR SPINNING AND TWISTING STICK-CANDY.

937,702.

Specification of Letters Patent. Patented Oct. 19, 1909.

Application filed January 4, 1908. Serial No. 409,283.

To all whom it may concern:

Be it known that I, DENNIS THOMAS IGOU, a citizen of the United States, residing at Springfield, in the county of Clark and State of Ohio, have invented certain new and useful Improvements in Machines for Spinning and Twisting Stick-Candy, of which the following is a specification, reference being had therein to the accompanying drawings.

This invention relates to machines for spinning and twisting stick candy.

The object of the invention is to provide an improved machine of this character which will spin the material into a strip of uniform diameter and provide the same with a uniform twist throughout its length.

To this end it is a further object of the invention to provide a machine of this character in which the spinning mechanism, together with the batch of material which is being operated upon, will rotate, while the spun or drawn out portion of the material will be held against rotation, thus imparting a twist to the drawn out portion after it leaves the spinning mechanism; to provide improved means for feeding the material to the spinning mechanism; to provide improved means for carrying off the drawn out or reduced portion of the material and holding the same against rotation; and to provide a machine of simple construction and of simple, but highly efficient operation.

With these objects in view my invention consists in certain novel features of construction and in certain parts and combinations hereinafter to be described, and then more particularly pointed out in the claims.

In the accompanying drawings, Figure 1 is a side elevation of a machine embodying my invention, partially broken away; Fig. 2 is a vertical sectional view on the line $\alpha\alpha$ of Fig. 1; Fig. 3 is an enlarged view of the upper portion of what is shown in Fig. 2; Fig. 4 is a transverse sectional view on the line $\alpha'\alpha'$ of Fig. 2; Fig. 5 is a sectional view of the diminisher on the line $z z$ of Fig. 2; Fig. 6 is a top plan view of the upper pair of spinning rollers showing the material as it is fed to said rollers; Fig. 7 is a

transverse sectional view of the spinning mechanism, taken on the line $y y$ of Fig. 2; Fig. 8 is a detail sectional view of the lower hollow trunnion for the spinning mechanism; Fig. 9 is a detail view of the locking mechanism for the hinged supporting frame for the spinning mechanism; Figs. 10 and 11 are detail views of the operating mechanism for the diminisher; Figs. 12 and 13 are detail views of the guide plate forming part of the conveying mechanism; Fig. 14 is a detail view of the operating mechanism for the spinning rollers; Fig. 15 shows a portion of the finished stick of candy; and Fig. 16 is a side elevation of the conveying mechanism.

In these drawings, I have illustrated the preferred form of my invention and have shown the same as mounted upon a suitable main frame 1 comprising a plurality of upright members 2 provided at intervals with suitable brackets or projections 3, adapted to receive and support the transverse members or plates 4, 5 and 6, upon which the various parts of the machine are mounted. The spinning and reducing mechanism preferably comprises a supporting frame mounted within the main frame 1 and between the transverse members 4 and 5 and is adapted to rotate about suitable hollow trunnions mounted in bearings carried by said transverse members. This supporting frame has mounted therein one or more pairs of spinning rollers adapted to engage the material and spin the same into a continuous strip or stick of uniform diameter. The supporting frame preferably comprises a pair of substantially parallel plates 7 and 8 provided at their upper and lower ends with hollow trunnions 9 and 10, which trunnions are journaled in suitable bearing apertures formed in the plates 4 and 5. A plurality of pairs of spinning rollers 11 are rotatably mounted between the plates 7 and 8, the rollers of each pair having their axes located in substantially the same horizontal plane and extending substantially parallel one to the other, and having their peripheries grooved to form a passage between said rollers. This groove, which is shown at 12, 100

is substantially semicircular in cross section, and, as the peripheries of the rollers of each pair lie very close one to the other, it will be seen that a substantially circular passage 5 is formed between said rollers. The width and depth of the groove 12 diminishes with each successive pair of rollers, being the greatest at the receiving end of the supporting frame and the least at the discharge end 10 thereof. These rollers are also of a greater width at the receiving end of the supporting frame in order to accommodate the larger width of the groove 12, and the rollers of each successive pair are of less width than 15 the rollers of the preceding pair and that portion of the plates 7 and 8 located between the successive pairs of rollers converges downwardly. The plates 7 and 8 are provided with a series of partitions 13 of a 20 width equal to the distance between said plates and located between the successive pairs of rollers on opposite sides of the passages formed between the same. Thus, it will be seen that a continuous inclosed conduit 14 is formed through the spinning mechanism, the spinning rollers extending into said conduit at intervals and being adapted to engage the material, feed the same through the conduit and spin the same 25 to a uniform diameter. Each successive pair of rollers preferably feeds the material at a slightly greater speed than does the preceding pair of rollers. Thus each pair of rollers exerts a pull upon the material and 30 prevents the same from piling up or accumulating between the successive pairs of rollers. This is accomplished in part by constructing each successive pair of rollers of a slightly greater diameter than the succeeding pair, whereby their peripheries move at a greater speed than do the peripheries of the preceding pair and is further accentuated by rotating the axles of 35 each successive pair of rollers at a greater speed than that at which the axles of the preceding pair of rollers is rotated. In order to afford ready access to the spinning rollers and to the interior of the conduit, one of the parallel plates is preferably 40 movably mounted relatively to the other. In the present form, the plate 7 is rigidly secured to the hollow trunnions 9 and 10 and occupies a fixed position relatively thereto, while the plate 8 is movably connected to the fixed 45 plate and can be swung away from the same. These plates are preferably connected by means of pivot lugs 15 and 16 extending from one side thereof and connected one to the other by suitable pivot pins 17. The opposite sides of the plates are provided with suitable means for locking the same in their normal or closed position, which, in the present instance, consists of one or more bolts 18 pivotally connected to a lug or lugs 50 19 carried by one of the bolts and adapted to engage a slotted lug 20 carried by the other plate, within which it is secured by means of a thumb nut 21, the slotted lug being provided with projections 22 to prevent the thumb nut slipping off the end of 55 the same. The partitions 13 are preferably rigidly secured to the fixed plate 7 by means of bolts 23 and remain at all times in the same relation to the spinning rollers and further serve as stops to limit the inward movement of the movable plate 8. The fixed plate 7 is provided with a plurality of bearings 24, in which are journaled shafts 25 which extend inwardly from said plate and have mounted thereon the spinning 60 rollers 11.

The ends of the shafts 25 extend beyond the spinning rollers and are adapted to engage suitable bearings carried by the movable plate 8. In the present instance, these 65 bearings comprise screw-threaded plugs 26 mounted in the plate 8 and having conical bearing recesses 27 adapted to receive the conical ends 28 of the shafts 25 and to serve as bearings to coöperate with the bearings 24 in supporting the shafts 25 between the plates 7 and 8, the screw-threaded plugs 26 being adjustable relatively to the plate 8 to bring the same into proper engagement with the ends of the shafts. The shafts 25 extend beyond the outer side of the plate 7 and are provided on their outer ends with suitable gears 29 for rotating the same. Movement may be imparted to said gears in any 70 suitable manner, but I prefer to actuate the same by the rotation of the supporting frame, thus maintaining the rotation of the spinning rollers at a uniform ratio to the rotation of the spinning mechanism as a whole. To this end, I provide a shaft 30 extending 75 longitudinally of the plate 7 and mounted in suitable bearing-lugs 31 carried thereby and provided with a plurality of pinions 32 adapted to coöperate with the gears 29 for rotating the several shafts 25. These gears and pinions are preferably both of the spiral type. The shaft 30 is provided at its lower end with a pinion 33 fixed thereto and adapted to engage a fixed circular rack or gear 34, which is secured to the transverse member 5 of the main frame and surrounds the trunnion 10 of the spinning mechanism. Thus, as the spinning mechanism is rotated about its longitudinal or vertical axis, the pinion 33 of the shaft 30 will travel over 80 the fixed rack 34 and will impart a rotary movement to said shaft and the pinions 32.

Rotary movement may be imparted to the spinning mechanism in any suitable manner, but I prefer to mount a bevel gear 35 upon the upper end of the trunnion 9 which extends above the plate 4 of the main frame. This gear is rigidly secured to said trunnion and is adapted to mesh with and to be rotated by a pinion 36 mounted upon one 85

end of a shaft which is journaled in a bearing 37 carried by the main frame and is provided on its outer end with suitable means, such as a pulley 38, for operatively connecting the same with a source of power.

Suitable conveying mechanism is provided for carrying away the drawn out or reduced portion of the material and for holding the same against rotation. This conveying mechanism preferably comprises a plurality of grooved rollers mounted upon a bracket 39 supported from the transverse member of the main frame and comprising two upwardly extending members, each having an arm 40 extending substantially at right angles thereto. A grooved roller 41 is mounted between the upwardly extending members of the bracket 39 and a second grooved roller 42 is mounted between the arms 40 of said bracket in substantially the same horizontal plane with the roller 41 and adapted to coöperate with that roller. The peripheral grooves of the rollers 41 and 42 are of a size approximately equal to the diameter 25 of the drawn out or reduced portion of the material and are adapted to engage the same and carry it away as it passes out through the lower hollow trunnion 10 of the spinning mechanism. A third grooved roller 43 is 30 preferably mounted between the upright members of the bracket 39 in substantially the same vertical plane as the roller 41 and has a peripheral groove corresponding to the groove of that roller. A suitable curved 35 guide plate 44 is supported from the arms 40 of the bracket 39 and extends between the passage formed between the rollers 41 and 42 and the passage formed between the rollers 41 and 43 and serves to guide the 40 strip of material from the first-mentioned passage to the second, thus causing the same to be fed outwardly at substantially right angles to the spinning mechanism. As stated, the passages between the rollers 41 45 and 42 and 41 and 43 are of substantially the same diameter as the reduced portion of the material and thus serve to engage the same and carry it away from the spinning mechanism and also serve to hold the same 50 against rotation. Thus, it will be seen that the rotation of the spinning mechanism and the mass of material carried thereby will cause a twist to be imparted to that part of the drawn out or reduced portion of the material which lies between the last pair of 55 spinning rollers and the conveying mechanism.

The rollers of the conveying mechanism are operated by the rotation of the spinning mechanism in any suitable manner, preferably by mounting a vertical shaft 45 in a bearing lug 46 carried by the bracket 39 and mounting a gear 47 on the upper end of said shaft, which gear is adapted to mesh 60 with a gear 48 mounted on the lower end of

the hollow trunnion 10, which extends below the transverse member 5. A bevel pinion 49 mounted on the opposite end of the shaft 45 meshes with a bevel gear 50 mounted on a transverse shaft 51 carrying the roller 41, 70 which shaft is provided on the opposite side of the bracket 39 with a gear 52 adapted to mesh with the gears 53 mounted on the transverse shafts 54 and 55 of the rollers 43 and 42, respectively, the relation of said 75 gears to the pinion 48 being such as to cause the rollers to move at substantially the same speed as do the last pair of spinning rollers 11. Thus, it will be seen that the spinning rollers will draw out or spin the material 80 into a cylindrical stick or strip of a uniform diameter throughout its length and that inasmuch as the rotation of the spinning rollers has a fixed relation to the rotation of the spinning mechanism as a whole, a uniform 85 twist will be imparted to the stick throughout its length.

A suitable support is mounted adjacent to the spinning mechanism and is adapted to receive the batch of material and feed the 90 same to the spinning mechanism. In the present instance, this support consists of a diminisher which is rotatably mounted on the main frame with its discharge end in alignment with the receiving end of the spinning mechanism and adapted to have its side walls moved toward and away from each other to compress the mass of material contained between the same and so diminish it in size as to enable it to pass through the 100 small discharge end of the diminisher. This diminisher preferably comprises a plurality of downwardly converging tapered plates 56 supported above the spinning mechanism and forming a receptacle within which the 105 batch of material to be spun is placed. A suitable sheet of flexible material 57 extends between the plates or members 56 and serves to prevent the escape of the material therefrom. These sheets are preferably of resilient material and are connected at their edges to the adjacent edges of the plates 56 and are of a width greater than the distance between the adjacent edges of said plates and are thus caused to bend inwardly, as shown 110 at Fig. 4. Suitable means are provided for moving the plates 56 inwardly or toward one another to compress the mass of material within the same, and, as this inward movement lessens the distance between the adjacent edges of the plates, the sheet of resilient material 57 is caused to bend inwardly and thus assists in compressing the material within the receptacle. When the plates 56 are again moved outwardly and the diameter 115 of the receptacle correspondingly increased, the material therein drops downwardly until it again comes into contact with the side walls of said receptacle. The diminisher may be supported in any suitable manner and any 120 125 130

suitable means may be employed for actuating the side walls thereof, but I prefer the form herein shown in which the diminisher is mounted within a frame or casing 58 extending about the same and having its side walls converging downwardly to correspond to the side walls of said diminisher and terminating a short distance above the lower end thereof where it is rigidly secured to a support or base portion 59, which, in turn, is rigidly secured at a point beneath the diminisher to the upper side of the bevel gear 35, which, as above stated, is fixed to the trunnion 9 of the spinning mechanism. The means for actuating the side walls of the diminisher consists of a plurality of levers 60 extending through apertures 61 in said casing or frame and pivotally mounted on said frame and adapted to move through a vertical plane. This lever 60 is preferably mounted on a horizontal pivot pin 62, mounted in a bracket 63 carried by said frame. The inner end of each of these levers is pivotally connected to one of the plates 56 at a point between the ends thereof, whereby, when the outer end of the lever is moved through a vertical plane, the plate, to which the inner end of said lever is connected, will be moved toward or away from said frame or casing. Any suitable means may be employed for actuating said levers, but I preferably employ some means which is actuated by the rotation of the diminisher, and, as here shown, this means consists of a connecting rod 64 connected at one end to the lever 60 by means of a universal joint 65, which is here shown as being of the ball and socket type, and at the other end to a band or strap 66 extending about an eccentric 67 formed on the outer face of a pinion 68, which, in turn, is journaled upon a suitable bearing stud 69 carried by the frame 58. Thus, it will be seen that the rotation of the pinion 68 and the eccentric 67 about the bearing stud 69 will move the rod 64 and the outer end of the lever 60 through a vertical plane.

The connecting rod 64 preferably has its opposite ends screw-threaded in opposite directions, as shown at 70 and 71, and adapted to engage correspondingly threaded sockets in the universal joint 65 and the band 66, thus enabling the same to be adjusted to regulate the length of throw of the inner end of the lever 60. The pinions 68 are adapted to mesh with a fixed annular rack or gear 72 which extends about the lower end of the diminisher, is fixed to the main frame and is preferably mounted on a bracket 73, which, in turn, is mounted upon the main frame 1. Thus, it will be seen that as the casing 58, within which the diminisher is mounted, rotates with the gear 35 and the spinning mechanism, the pinions 68 will travel over the rack 72 and will be ro-

tated, thereby causing the cam 67, which rotates in unison therewith, to actuate the lever 60, which, in turn, actuates the downwardly converging plates of the diminisher and causes the mass of material which is contained therein to be reduced in size and fed through the lower end of said diminisher to the spinning mechanism. Suitable means are provided for causing the plates 56 to move a uniform distance throughout their length. This means preferably consists of links 60^a of a length equal to that portion of the lever 60 lying between the pivoted pin 62 and the plates 56 and extending at substantially the same angle to said plates. The plates 56 of the diminisher preferably extend substantially parallel one to the other for a short distance at a point near the lower ends thereof, as shown at 74, and these parallel portions of the plates are so arranged that the opening through the same is of greater width in one direction than in the other, and this greater width extends transversely of the shafts 25 carrying the spinning rollers 11. Thus, the material is fed from the diminisher in a strip, the diameter of which in a direction transversely of the axes of the spinning rollers is greater than the diameter of the passage between the first pair of said rollers and the diameter in a direction parallel with said axes is less than the diameter of said passage, thereby enabling the strip of material to enter the passage without coming into contact with the sides of the grooves and preventing the material from being forced over the sides of the grooves and between the peripheries of the rollers.

The diminisher is provided with a hopper by means of which the material is fed to the diminisher. This hopper is here shown as comprising a casing 75 open at both ends, its lower end extending into the upper end of the diminisher and provided with outwardly extending flanges 76, by means of which it is supported on the upper end of the casing 58. Thus, as a batch of material is worked downwardly in the diminisher, a second batch may be placed in the hopper, and, as both batches are in a soft plastic condition, those portions thereof which come in contact will unite and form a single batch of material, thus enabling the material to be fed to the spinning rollers in a continuous strip.

The operation of the machine will be readily understood from the foregoing descriptions of the several parts thereof and it will be seen that I have provided a machine of this character, in which the spinning and reducing mechanism, the feeding apparatus and the batch of material carried thereby are rotated about a common axis and that the material is carried through said spinning mechanism and gradually reduced

in size or spun out into a strip or stick of uniform diameter throughout its length, the stick being reduced in size as it is drawn from the diminisher by the first pair of rollers and then further reduced by each succeeding pair of rollers that such stick is engaged by the spinning rollers located between the spinning mechanism and carried to one side of the machine, where it may be deposited on a suitable conveyor for removing the same; and further, that this reduced or spun out portion of the material is held against rotation and thus a twist imparted to that part of the reduced portion of the material lying between the last pair of spinning rollers and the conveying rollers. This twist, which is shown by the stripe 77, is uniform throughout the length of the stick owing to the fact that the feed of the material through the spinning mechanism and the rotation of said spinning mechanism are in a fixed ratio one to the other. Further, it will be seen that I have produced a machine for accomplishing this result which is simple in its construction and operation, and, at the same time, highly efficient in operation.

I wish it to be understood that I do not desire to be limited to the exact details of construction shown and described, for obvious modifications will occur to a person skilled in the art.

Having thus fully described my invention, what I claim as new and desire to secure by Letters Patent is:—

- 35 1. A machine of the character described comprising a main frame, spinning and reducing mechanism mounted thereon, means for supporting a batch of material adjacent to said spinning and reducing mechanism, means for rotating said spinning and reducing mechanism and batch of material, and means for holding the reduced portion of said batch of material against rotation.
- 40 2. A machine of the character described comprising a main frame, a support rotatably mounted thereon and adapted to receive a batch of material, spinning and reducing mechanism rotatably mounted on the frame adjacent to said support and in alignment therewith, means for rotating said support and said spinning and reducing mechanism, and means for holding the reduced portion of said batch of material against rotation.
- 45 3. A machine of the character described comprising a main frame, a support rotatably mounted thereon and adapted to receive a batch of material, spinning and reducing mechanism rotatably mounted on said frame adjacent to said support and in alignment therewith, means for rotating said support and said spinning and reducing mechanism, and conveyor mechanism supported adjacent to said spinning mechanism and adapted to receive the reduced portion

of said batch of material and hold the same against rotation.

4. A machine of the character described comprising a main frame, spinning and reducing mechanism rotatably mounted thereon, a diminisher rotatably supported adjacent to said spinning and reducing mechanism and adapted to support a batch of material and feed the same to said spinning and reducing mechanism, means for rotating said diminisher and said spinning and reducing mechanism, and means for holding the reduced portion of said batch of material against rotation.

5. A machine of the character described comprising a main frame, spinning and reducing mechanism rotatably mounted on said frame, a diminisher rotatably mounted on said frame and so connected to said spinning and reducing mechanism as to move in unison therewith, and means for rotating said spinning and reducing mechanism.

6. In a machine of the character described, spinning and reducing mechanism comprising a vertically arranged, rotatable supporting frame, a plurality of pairs of rollers mounted on said frame, the rollers of each pair having their axes parallel and in substantially the same horizontal plane, and means for so actuating said rollers as to cause the several pairs thereof to feed the material forward at different speeds.

7. In a machine of the character described, spinning and reducing mechanism comprising a vertically arranged, rotatable supporting frame, a plurality of pairs of rollers mounted on said frame, the rollers of each pair having their axes in substantially the same horizontal plane, having their adjacent sides parallel and having grooves in their peripheries to form a passage between the same, and means for so actuating said rollers as to rotate the same in opposite directions and to cause the several pairs thereof to feed the material forward at different speeds.

8. In a machine of the character described, spinning and reducing mechanism comprising a rotatable supporting frame, a plurality of pairs of rollers mounted on said frame, the rollers of each pair having their adjacent sides parallel and having grooves in their peripheries to form a passage between said rollers, the rollers of each successive pair being of greater diameter than the rollers of the preceding pair, pinions for actuating said rollers, the pinions of each succeeding pair of rollers being of less diameter than the pinions of the preceding pair, thereby causing each successive pair of rollers to feed the material at a greater speed than it is fed by the preceding pair of rollers and means operated by the rotation of said supporting frame for actuating said pinions.

9. In a machine of the character described, spinning and reducing mechanism comprising

- ing a supporting frame, a plurality of pairs of rollers mounted on said frame, the rollers of each pair having their axes parallel and having grooves in their peripheries to form 5 a passage between said rollers, each successive pair of rollers being of greater diameter than the preceding pair and means for rotating each successive pair of rollers at a greater speed than that at which the preceding pair 10 of rollers is rotated.
10. In a machine of the character described, spinning and reducing mechanism comprising a supporting frame, a plurality of pairs of rollers mounted on said frame, 15 the rollers of each pair having their axes parallel and having grooves in their peripheries to form a passage between said rollers, each successive pair of rollers being of greater diameter than the preceding pair, 20 and the grooves in each successive pair of rollers being of less depth than the grooves in the preceding pair of rollers.
11. In a machine of the character described, spinning and reducing mechanism comprising a pair of plates hinged one to the other, a plurality of pairs of rollers mounted between said plates, and means for 25 rotating said rollers.
12. In a machine of the character described, a pair of plates, one of said plates being fixed and the other plate being adapted to be moved toward and away from said fixed plate, shafts journaled in said fixed plate, bearings carried by said movable plate and adapted to engage the adjacent ends of said shafts, rollers mounted on said shafts, and means for 30 rotating said shafts.
13. In a machine of the character described, spinning and reducing mechanism comprising a pair of plates, one of said plates being fixed and the other plate being adapted to be moved toward and away from said fixed plate, a plurality of pairs of shafts journaled in said fixed plate, bearings carried by said movable plate and adapted to engage the adjacent ends of said shafts, rollers mounted on said shafts, partitions carried by one of said plates and extending between the successive pairs of rollers, and means for 35 rotating said shafts.
14. In a machine of the character described, spinning and reducing mechanism comprising a pair of plates means for rotating the same about a longitudinal axis, a plurality of pairs of rollers mounted between said plates, the rollers of each successive pair being of less thickness than the rollers of the preceding pair, the adjacent surfaces of said plates converging downwardly in the space between said pairs of rollers, and means for rotating said rollers.
15. In a machine of the character described, a main frame, bearings carried by said main frame, spinning and reducing mechanism comprising a supporting frame, hollow trunnions at the opposite ends of said supporting frame adapted to engage said bearings, means for rotating said supporting frame in said bearings, a plurality of pairs of rollers mounted on said supporting frame, each pair of said rollers having their axes parallel and having their peripheries grooved to form a passage between said rollers, and means for rotating said rollers.
16. In a machine of the character described, a main frame, bearings carried by said main frame, spinning and reducing mechanism comprising a supporting frame, hollow trunnions at the opposite ends of said supporting frame adapted to engage said bearings, means for rotating said supporting frame in said bearings, a plurality of pairs of rollers mounted on said supporting frame, a circular rack secured to said main frame and surrounding one of said trunnions, a shaft extending longitudinally of said supporting frame and adapted to rotate therewith, a pinion secured to said shaft and adapted to engage said circular rack, other pinions fixed on said shaft, and gears connected to said rollers and adapted to be engaged by said other pinions.
17. In a machine of the character described, a main frame, bearings carried by said main frame, spinning and reducing mechanism comprising a supporting frame, hollow trunnions at the opposite ends of said supporting frame adapted to engage said bearings, means for rotating said supporting frame in said bearings, a plurality of pairs of rollers mounted on said supporting frame, a circular rack secured to said main frame and surrounding one of said trunnions, a shaft extending longitudinally of said supporting frame and adapted to rotate therewith, a pinion secured to said shaft and adapted to engage said circular rack, other pinions fixed on said shaft, said other pinions decreasing in diameter as they approach one end of said shaft, and gears connected to said rollers and adapted to be engaged by said other pinions.
18. In a machine of the character described, a diminisher comprising a plurality of downwardly converging plates having their lower ends spaced apart to form an outlet, the diameter of said outlet taken in one direction being greater than the diameter thereof taken in another direction, and means for moving said plates inwardly at intervals to compress the material within the same.
19. In a machine of the character described, a diminisher comprising a plurality of downwardly converging plates, sheets of resilient material extending between and connected to the adjacent edges of said

plates, and means for moving said plates inwardly at intervals to compress the material within the same.

20. In a machine of the character described, a diminisher comprising a frame, a plurality of downwardly converging plates within said frame, inwardly curved sheets of resilient material extending between and connected to the adjacent edges of said plates, and means for moving said plates inwardly at intervals to compress the material within the same.

21. In a machine of the character described, a diminisher comprising a frame, a plurality of downwardly converging plates within said frame having their lower ends free; a plurality of levers mounted on said frame, each lever having its inner end connected to one of said plates at a point between the ends thereof, means for moving said lever about its pivotal center, and a link connecting said plate to said frame at a point above said lever.

22. In a machine of the character described, a diminisher comprising a frame, a plurality of downwardly converging plates within said frame, a plurality of levers mounted on said frame, each lever having its inner end connected to one of said plates, and cam actuated means for moving said lever about its pivotal center.

23. In a machine of the character described, a diminisher comprising a frame, a plurality of downwardly converging plates within said frame, a plurality of levers mounted on said frame, each lever having its inner end connected to one of said plates, a cam rotatably supported near said lever, means for connecting the outer end of said lever with said cam, and means for actuating said cam.

24. In a machine of the character described, the combination, with the main frame, of a diminisher comprising a frame, a plurality of downwardly converging plates within said frame, a plurality of levers pivotally mounted on said frame, each of said levers having its inner end connected to one of said plates, a plurality of pinions rotatably supported on said frame, a cam mounted on each pinion, a ring extending about each of said cams, a connecting rod connecting said ring with the outer end of the adjacent levers, means for rotating the frame of said diminisher, and a rack carried by said main frame and adapted to mesh with said pinions and actuate said levers.

25. In a machine of the character described, a diminisher comprising a plurality of downwardly converging plates, means for moving said plates inwardly at intervals to compress the material within the same, and a hopper supported above said diminisher.

26. In a machine of the character de-

scribed, the combination, with spinning and reducing mechanism, and means for rotating the same about a longitudinal axis, of conveying mechanism held against rotation about a longitudinal axis and comprising a plurality of rollers having a passage between the same, and means for actuating said rollers about their horizontal axes by the rotation of said spinning mechanism.

27. In a machine of the character described, the combination, with a main frame, spinning and reducing mechanism comprising a supporting frame having hollow trunnions journaled in said main frame, spinning rollers carried by said supporting frame, and means for rotating said supporting frame, of a conveying mechanism located adjacent to one of said hollow trunnions and comprising a plurality of rollers, passages formed between said rollers and extending at substantially right angles one to the other, a shaft supporting one of said rollers and having a bevel pinion on the outer end thereof, a second shaft rotatably supported near said first-mentioned shaft and having a bevel pinion adapted to mesh with the first-mentioned bevel pinion, a gear on the other end of said last-mentioned shaft, and a pinion carried by the adjacent trunnion of said supporting frame and adapted to mesh with said gear.

28. In a machine of the character described, spinning and reducing mechanism comprising a supporting frame, a pair of spinning rollers mounted in said supporting frame, each of said rollers having grooves in the periphery thereof to form a substantially circular passage between said rollers, and feeding mechanism mounted above said supporting mechanism and adapted to feed the material to said rollers in a strip having its greatest diameter extending transversely of the axes of said rollers.

29. In a machine of the character described, spinning and reducing mechanism comprising a pair of spinning rollers, means for rotating said rollers about their axes, means for rotating said pair of rollers about an axis extending at substantially right angles to the axes of said rollers, conveying mechanism arranged to receive the material from said spinning and reducing mechanism and to hold the same against rotation, whereby the rotation of said pair of rollers will twist the material.

30. In a machine of the character described, spinning and reducing mechanism comprising a supporting frame, spinning rollers mounted therein and adapted to rotate about horizontal axes, means for rotating said supporting frame about a vertical axis, and conveying mechanism arranged to receive the material from said spinning and reducing mechanism and to hold the same

against rotation, whereby the rotation of said supporting frame will twist the material.

31. In a machine of the character described, the combination, with spinning and reducing mechanism, and means for rotating the same, of conveying mechanism having a discharge passage at an angle to said spinning and reducing mechanism and adapted

to hold the reduced portion of the material to against rotation.

In testimony whereof, I affix my signature in presence of two witnesses.

DENNIS THOMAS IGOU.
